JOSEPH F. DEMERS, OF BERWICK, MAINE.

LUG CONNECTION FOR PICKER-STICKS.

1,292,723.

Specification of Letters Patent. Patented Jan. 28, 1919.

Application filed April 13, 1918. Serial No. 228,337.

To all whom it may concern:

Be it known, that I, JOSEPH F. DEMERS, of Berwick, in the county of York and State of Maine, a citizen of the United States, have invented a new and useful Improvement in Lug Connections for Picker-Sticks, of which the following is a full, clear, and exact description, reference being had to the accompanying drawings, forming a part of this specification, in explaining its nature.

The present invention relates to the connection between the so-called "picker stick" and the picker arm of a loom and by which connection the motion of the picker arm is imparted to the picker stick for operating it.

As now customarily employed in looms the connection between the picker stick and picker arm comprises a connecting bar having U-shaped strap ends embracing the stick and arm respectively. The straps are made of canvas, leather or similar material. They are secured to the opposite ends of the bar by bolts and at the points where the bolts pass through the straps they are slotted in order to provide for their endwise adjustment in relation to the bar. These connections in many ways are satisfactory as long as they last for they are inexpensive and require no specially preformed parts, or, in other words, are made of stock parts easily procurable, and provide for an adjustment of the strap ends both in relation to the picker stick and the picker arm. A disadvantage of the connection, however, is that the strap ends become very quickly worn out and are also easily broken or disrupted by the strain to which they are subjected. Another disadvantage is that the strap ends will get out of adjustment in case of any loosening of the bolts which connect them to the bar, and which loosening would not be apparent. This necessitates the shutting down of the loom for an appreciable length of time in order to provide for the further adjustable fixing of the strap end or ends.

The object of my invention is to retain in a lug connection all of the advantages now obtainable in the connection to which I have referred and as ordinarily employed, and to overcome the disadvantages; in other words, to provide a lug connection inexpensive to manufacture, with parts easily procurable; to provide a lug connection

which will be wear-resisting and practically unbreakable under ordinary conditions of usage; to provide a connection permitting of all required adjustments of the strap ends, both in relation to the picker stick and the picker arm; to provide a lug connection in which loosening of the fastenings for securing the strap ends will be made apparent to the operator, and to provide a connection in which the loosening of the connection for the strap ends will not disturb their adjustment before such loosening can be corrected.

My invention can best be seen and understood by reference to the drawings, in which—

Figure 1 shows in side elevation the connection as applied to a picker stick and picker arm, those parts of the stick and arm only being shown for a proper understanding of the invention.

Fig. 2 is a section on the line 2—2 of Fig. 1.

Figs. 3 and 4 show in perspective the strap ends, which form elements of the connection which will later be explained.

Figs. 5 and 6 show modified structures of the strap ends.

Referring to the drawings:—

1 represents the usual pick arm which operates the pick stick. 2 is the pick stick and 3 the connection between the arm and stick by which the motion of the arm is communicated to the stick for operating it, and in which connection resides the subject-matter of my invention.

The connection 3 comprises separate end straps 5 and 6 and an interposed piece or bar 7 to which the straps are secured.

The straps 5 and 6 consist of flat metal pieces bent into U-shape with the free ends of the straps or strap arms overlapping the ends of the interposed bar 7 and bearing against the opposite sides thereof.

The bar 7 is preferably made of wood rectangular in general shape, with widened ends forming offsets against the outer faces of which the strap arms bear.

The straps are secured to the bar 7 by means of bolts 9 which pass through the strap arms and bar and are secured by nuts 10. The strap arms are provided with longitudinal slots 11 where the bolts pass through them in order to provide for the endwise or longitudinal adjustment of the

straps with relation to the bar 7 to which they are secured. Further retention of the straps in their relation to the bar is effected as follows:

5 Affixed to the outer sides of the strap arms are facings 12 preferably made of leather or other tough though indentable material. The facings are secured to the arms by riveting or other suitable mode of 10 retention. The width of these facings is substantially the same as that of the arms and their length is such that the facings will extend well beyond the ends of the slots 11 formed in the arms, these slots being 15 formed also in the leather facings.

Arranged upon the bolts 9 and retained by the heads of the bolts and nuts 10 to bear against the facings 12 in the strap arms, are grips 14 which, upon the tightening 20 of the nuts for securing the bolts, are pressed into engagement with the facings 12 for holding the straps in place against endwise displacement.

Each of the grips 14 consists of a metal 25 plate having a hole in it for receiving the bolt; a corrugated inner face 15 by which it may bite into the leather facing upon application of pressure to the back of the grip, and flanges 16 depending from the 30 sides of the grip, which overlap the side edges of the facing. The flanges 16 hold the grips in alinement with the strap arms and leather facings thereon and prevent the grips from turning relatively thereto.

35 In Figs. 5 and 6 there is shown a modification of my invention in that instead of applying leather facings to the strap arms, the outer faces of the strap arms are provided with corrugations 17 and the corrugated inner faces 15 of the grips 14 mesh directly therewith. This construction is 40 more expensive than the one first referred to which employs the leather facings. For ordinary purposes the leather facings are entirely satisfactory inasmuch as the corrugated faces of the grips bite into the leather and form corrugations in it, the leather thus corrugated preventing any 45 tendency to frictional displacement under ordinary usage. In cases, however, where the straps may be subjected to undue strain tending to displace them the modified construction, or that last referred to, may be 50 employed.

55 In the application of the lug connection the lug strap 5, which embraces the pick stick, is supported in the usual manner by a leather loop 18 which is attached to the pick stick by a screw 19. The strap 6, which 60 embraces the pick arm, is provided preferably with a lining 20 of leather, any suitable piece of strap leather being adaptable for this purpose. This lining is usually made of stiff leather and maintains its place when 65 bent by its frictional bearing against the

interior of the strap arm although the strap may be riveted or otherwise fastened to the arm if desired.

The lug connection thus provided is, in accordance with the objects of my invention, 70 inexpensive, made of parts easily procurable, and practically impervious to breakage or wear. In fact, the leather loop 18 and lining 20 of the metal straps provide renewable wearing parts for taking up wear 75 which might otherwise come upon them.

The connection permits of all required 80 adjustments of the strap ends both in relation to the picker stick and the picker arm. The means for securing the straps to their connecting bar permits of an easy adjustment of the straps and, when the fastening is made properly tight, operates to hold the straps securely in place.

Another very decided advantage from an 85 operating standpoint resides in the fact that in case the fastening for the strap should become partly released or loosened such loosening will not result in a loss of adjustment 90 of the strap, but will simply allow the strap to turn upon the bar to which it is attached, which turning immediately notifies the operator of the loosening of the connection and correction can be made before the loosening has gone so far as to effect displacement 95 of the strap as regards its adjustment. In other words, all the operator need do, in case the fastening becomes loosened, is to turn the strap back into proper position and retighten the fastening nut, further adjustment of the strap being unnecessary. 100

Having thus fully described my invention, I claim and desire to secure by Letters Patent of the United States:

1. A lug connection of the type specified 105 having a strap-carrying bar, a strap carried by the bar and adjustable endwise in relation to it, and a fastening for securing the strap to the bar, said fastening comprising means permitting of the turning of the 110 strap with relation to the bar without endwise displacement of the strap upon a partial release or loosening of said fastening and permitting of the endwise displacement or adjustment of the strap upon a more complete release of said fastening. 115

2. A lug connection of the type specified 120 having a strap-carrying bar, a strap carried by the bar and adjustable endwise in relation to it, said strap having arms overlapping the end of said bar, a releasable fastening for securing the strap arms to the bar and permitting of the endwise displacement of the strap and of the strap turning upon the bar upon the release of said fastening, said fastening comprising in part 125 means functioning to permit of the turning of said arms and strap on said bar upon the partial release or loosening of said fastening and of the endwise displacement or 130

adjustment thereof only upon a more complete release of said fastening.

3. A lug connection of the type specified having a strap-carrying bar, a strap carried by the bar and adjustable endwise in relation to it, and a fastening for securing the strap to the bar, said fastening comprising in part gripping devices held by it and functioning to permit of the turning of the strap with relation to the bar without endwise displacement thereof upon a partial release or loosening of said fastening and of the endwise displacement or adjustment of the strap upon a more complete release of said fastening.
4. A lug connection of the type specified having a strap-carrying bar, a strap carried by the bar and adjustable endwise in relation to it, said strap having arms overlapping the end of the bar, a bolt-and-nut fastening for securing the strap to the bar, and gripping devices retained by said bolt-and-nut fastening and functioning to permit of the turning of the strap with relation to the bar without endwise displacement thereof upon a partial release or loosening of said fastening and of the endwise displacement or adjustment of the strap upon a more complete release of said fastening.
5. A lug connection of the type specified having a strap-carrying bar, a strap carried by the bar, said strap having slotted arms overlapping the end of said bar and bearing against the same, a bolt-and-nut fastening for securing the strap to the bar

with the bolt passing through said bar and through said arms at the points of the slots therein, and gripping devices retained by said bolt-and-nut fastening to bear against said arms for holding said strap, said arms of the strap presenting faces with which gripping devices will have interlocking engagement.

6. A lug connection of the type specified having a strap-carrying bar, a metal strap carried by the bar with arms overlapping the end of the bar and bearing respectively against the opposite sides thereof, said arms having slots formed in them, a releasable fastening for securing the strap arms to the bar, said fastening extending through the bar and through the slots in said arms and permitting of both endwise adjustment of said strap in relation to said bar and the turning of the strap thereon when said fastening is released, and gripping devices retained by said fastening to engage said arms for holding the strap in place upon the tightening of said fastening, said arms of the strap presenting facings with which said gripping devices have interlocking engagement whereby said strap will be held in place when said fastening is properly tightened and whereby, also, said strap may turn in relation to said bar upon a partial release or loosening of said fastening and the endwise displacement or adjustment of said strap in relation to said bar only permitted upon a more complete release of said fastening.

JOSEPH F. DEMERS.
